CONDUIT OUTLET BOX

Earnest J. Dillman, Detroit, and Frank John Sovey, Roseville, Mich., assignors to Detroit Lubricator Company, Detroit, Mich., a corporation of Michigan

Application November 20, 1934, Serial No. 753,832

3 Claims. (Cl. 247—14)

Our invention relates to new and useful improvements in outlets for electrical conduits, and has particular reference to an outlet box for such conduits, which may be readily adapted for use with electric switches or other control apparatus.

An object of our invention is to provide a simple and readily accessible outlet closure which will permit a rapid, safe, electrically perfect connection to be made between an electrical accessory and a power line.

Another object of the invention is to provide an outlet box which is light in weight, yet durable, and one in which the connecting means are fully enclosed and protected from dirt, oil, moisture and other elements which might cause corrosion and impair the electrical efficiency of the equipment with which the device is used.

The invention consists in the improved construction and in the combination and arrangement of parts to be more fully described herein-after, the novelty of which will be particularly pointed out and distinctly claimed.

In the accompanying drawing, which constitutes part of our disclosure, we have fully and clearly illustrated a preferred embodiment of our invention, in which drawing—

Fig. 1 is a top plan view of our device with the casing or cover member removed.

Fig. 2 is a vertical sectional view taken on the line 2—2 of Fig. 4.

Fig. 3 is a bottom plan view of the device.

Fig. 4 is an end view looking from right to left of Fig. 2.

Fig. 5 is an enlarged fragmentary sectional view taken on line 5—5 of Fig. 1.

Fig. 6 is an enlarged fragmentary view partly in section taken on line 6—6 of Fig. 5.

Referring now to the drawing by characters of reference, 8 designates a base member, which is preferably made of an electric insulating material, such as hard rubber, bakelite, or other plastic molding material, and is formed with an internally threaded, cylindrical end portion 9, and an oppositely disposed, substantially flat, bull nosed portion 10, and a centrally disposed upstanding substantially circular portion 11, which is provided with a flat abutment side face 12 and an inset 13.

The flat portion 10 of the base 8, is provided with two vertical passageways 14 and 15, adapted to receive screws or bolts (not shown), so that the device may be readily attached to another device, such as the stack control switch of an oil burner system, or any other device that requires a connection to an electric power line. It will be

noted that the passageway 15 terminates within the interior of the device, so that a screw or bolt cannot be inserted therein or removed without first uncovering the device.

A longitudinally extending recess 16, Fig. 1, 5 having diverging sidewalls 17 and an under cut bottom wall 18, is formed in the upstanding portion 11, of the base member 8, and communicates, at its point of greatest divergence, with the interior of the internally threaded cylindrical portion 9.

Angularly positioned, with reference to the long axis of the device, and molded in the upstanding portion 11, of the base member 8, are two rectangular shaped terminal blocks 19 and 20, preferably made of a high conductive hard metallic substance, and formed with an undercut portion 21, Fig. 5, near their bases which serve as anchor means for said blocks. The blocks 19 and 20 are provided with vertical passageways 22 20 and 23, which communicate with counterbored passages 24 and 25, which vertically pass through the flat portion 10, of the base 8, and extend into the upstanding portion 11 of the same member. Set screws 26 are arranged to engage internally 25 threaded passageways 27, Fig. 6, formed near the top of said blocks 19 and 20, at right angles to the vertical passageways 22 and 23. The sidewalls of the blocks 19 and 20 are recessed so that the heads of the set screws 26 may be carried 30 flush with the walls of the blocks. The blocks 19 and 20 are also provided with set screws 28 and 29, Fig. 1, which are vertically mounted in threaded passageways formed therein. The top faces of the blocks 19 and 20 are recessed so that the 35 heads of the set screws 28 and 29 may ride flush with the tops of the said blocks.

A round cover member or cap 30, preferably made of the same material as the base 8, is formed with a knurled outer periphery 31, depending side walls 32, and an interiorly depending centrally disposed round portion 33, Fig. 2, in which is molded an internally threaded, metallic insert 34, which is arranged to engage an externally 40 threaded, centrally disposed, metallic tie rod 35, which is vertically molded into the flat portion 10 of the base 8, and anchored therein by the 45 undercut portion 36.

The lower edges 37 of the depending sidewalls 50 32, of the cap 30, are smoothly finished, in order to make close contact with the upper face 41, of the upstanding portion 11, of the base 8, and overhang the latter, somewhat, so that dirt and moisture are less apt to penetrate between the 55

base 8 and cap 30 into the chamber formed between said base and said cap.

To assemble and use the device, it is first preferably fastened, by means of the internally threaded cylindrical portion 9, to the end of the power line conduit, so that the power line leads extend through the recess 16. One of the power line leads is then inserted horizontally under the set screw 28, and the set screw 28 is tightened. The other power line lead is similarly secured in place by the set screw 29.

One of the leads from the switch or other electrical accessory (not shown) is then passed upwardly through the passageway 24 formed in the base 8, and thence through the passageway 22 formed in the block 19, and is tightly secured in place by the set screw 26. The second lead from the switch or other accessory, is then passed upwardly through the passageway 25 formed in the base 8, and thence through the passageway 23 formed in the block 20, and is tightly secured in place by the set screw 26. The base 8 is then secured to the switch or other accessory by means of screws or bolts which are extended through the passageways 14 and 15, care being had that there is proper alignment of the lead wire holes so that the leads do not become pinched or injured. The cover member 30 is then screwed onto the tie rod 35 until the lower edges 37 of the cover 30 abut tightly against the upper face 41 of the round portion 11, and the device is ready to operate.

Having described our invention, what we claim and desire to secure by Letters Patent is:

1. A conduit outlet box comprising a hollow base member of cup-like form defining a chamber for the end portion of a lead wire, a wall of said base member having an aperture therethrough opening into said chamber for admission of the lead wire end portion, a post secured to the inner bottom wall of said chamber, said base member having a seating surface normal to and surrounding said post, a cover member having an internal socket facing said post, a terminal post secured to said base member adjacent said post and covered by said cover member, means for securing the lead wire entering said chamber to said terminal post, said cover member having a seating surface normal to said first-named post and cooperable with said first-named seating surface, said first-named post and said socket having cooperable means to hold the seating surfaces of said cover member and said base member

tightly in engagement with each other upon movement of said surfaces into engagement, and said base member having an aperture for admission of a lead wire to said terminal post.

2. A conduit outlet box comprising a hollow base member of cup-like form defining a chamber for lead wire end portions, a wall of said base member having an aperture therethrough opening into said chamber for admission of the said portions thereinto, a screw-threaded post secured to the inner bottom wall of said chamber, said base member having a seating surface normal to and concentric with said post, a hollow cover member of cup-like form defining a chamber cooperable with said base member chamber to form a compartment, terminal posts secured to said base member at the sides of said post and positioned in said compartment, means cooperable with said terminal posts to secure the lead wire portions thereto, said cover member having an inwardly opening internally screw-threaded socket rigid with said cover member and facing said threaded post, said cover member having a seating surface normal to said threaded post and concentric with said socket and said post, said surfaces being movable into tight clamping engagement with each other upon threading of said cover member by its rotation onto said threaded post, said base member having apertures aligned with and for admission of lead wires to said terminal posts from external of said base and said cover member, and means cooperable with said terminal posts for securing thereto the lead wires entering said last-named apertures.

3. In a conduit outlet box, a hollow body comprising separable and cooperable base and cover members, means for clamping said members together, said body having an opening through a wall thereof, a terminal post within said body and closing the inner end of said opening, said post having a longitudinal aperture for receiving a lead wire entering through said opening, a screw threaded into said post and cooperable with said aperture for holding the lead wire tightly in said aperture, said post having in its inner end a longitudinal screw-threaded opening, a screw adjustable in said threaded opening, said body having a second opening through a wall thereof for admission of a lead wire to be secured to said post by said adjustable screw.

EARNEST J. DILLMAN.
FRANK JOHN SOVEY.
